UNITED STATES PATENT OFFICE.

ELMER BELL, OF MOUNT PLEASANT, PENNSYLVANIA.

DESIGN FOR A TUMBLER OR SIMILAR ARTICLE.

Application filed August 12, 1925. Serial No. 14,402. Term of patent 3½ years.

To all whom it may concern:

Be it known that I, ELMER BELL, a citizen of the United States, and resident of Mount Pleasant, in the county of Westmoreland and State of Pennsylvania, have invented a new, original, and ornamental Design for Tumblers or Similar Articles, of which the following is a specification, reference being had to the accompanying drawings, forming part hereof, in which:—

I claim:

The ornamental design for a tumbler or similar article as shown.

In witness whereof, I have hereunto set my hand.

ELMER BELL.
